UNITED STATES PATENT OFFICE.

GEORGE M. LANDERS, OF NEW BRITAIN, CONNECTICUT, ASSIGNOR TO THE
LANDERS, FRARY & CLARK, OF SAME PLACE.

DESIGN FOR A KNIFE-HANDLE.

SPECIFICATION forming part of Design No. 33,728, dated December 18, 1900.

Application filed November 20, 1900. Serial No. 37,177. Term of patent 7 years.

To all whom it may concern:

Be it known that I, GEORGE M. LANDERS, a citizen of the United States, residing at New Britain, in the county of Hartford and State 5 of Connecticut, have invented and produced a new and original Design for Knife-Handles, of which the following is a specification, reference being had to the accompanying drawings, forming part thereof.

Figure 1 is a side elevation of a knife-handle, showing my new design. Fig. 2 is a plan view, and Fig. 3 an end view, of the same.

As shown in the drawings, the contour of the handle in side view has parallel straight 15 upper and lower edges 4 at the blade end of the handle, which straight edges extend to about half the length thereof, then curve outwardly to the widest portion near the butt 6, and then curve around the butt and meet 20 each other, as shown. On each side of the handle there is a flat face 7 of the same gen-

eral contour as the handle, and around the edge there is a plane face 8, about one-third as wide as the handle is thick. Between these edge and side faces 7 and 8, at the top, bottom, 25 and butt-end, there is a rounded bead 9, with a border-shoulder 10 on each side thereof. At the front or blade end of the handle the corners are beveled off with a concave face 11. On each of the flat side faces 7, near the 30 front end, is a rounded projection 12, all combined in a simple and pleasing unitary design.

Having described my invention, what I claim as new, and desire to secure by Letters 35 Patent, is—

The design for a knife-handle, as herein shown and described.

GEORGE M. LANDERS.
